[57] CLAIM

The ornamental design for a low profile computer bezel, as shown and described.

DESCRIPTION

FIG. 1 is a perspective view of a low profile computer bezel showing my new design, the computer housing being shown in broken lines for illustrative purposes only and forms no part of the claimed design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of a second embodiment of my design;

FIG. 8 is a front elevational view of a third embodiment of my design.

The undisclosed views of the second and third embodiments are similar in appearance to those of the first embodiment.

FIG. 1

FIG. 5

FIG. 2

FIG. 3

FIG. 4

FIG. 6

FIG. 7

FIG. 8
